EASY OPENING CONTAINER

Frederick W. Negus, Fond du Lac, and Oscar H. Williamson, Neenah, Wis., assignors to International Paper Company, New York, N.Y., a corporation of New York

Filed Oct. 21, 1959, Ser. No. 847,813

1 Claim. (Cl. 229—51)

This invention relates to paper board shipping containers, and more particularly to an end loading corrugated container having quick opening features for packaging canned food and beverages.

It is desirable to form one-piece blanks in a continuous operation with as little waste as possible, to provide a partially formed blank which can be shipped in flat condition to save space and freight charges and which can then be erected, filled and sealed to form a strong compact container for contents such as twenty-four cans of beer, which can withstand the stresses of shipping and handling and which can then be rapidly and easily opened by hand by the ultimate consumer.

The container of the invention is particularly well adapted for rapid efficient production on automatic container blank forming machinery, for shipping in knocked down flat condition and for rapid erection, filling and closing with automatic packaging machinery and finally for quick opening by the consumer.

These and other objects and advantages are provided by the container described and claimed herein in connection with the drawings, in which:

FIG. 1 is a plan view of the flat-one-piece blank from underneath, i.e. inside the erected box;

FIG. 2 is a perspective of the blank partially formed and being erected from flat into rectangular condition;

FIG. 3 is a perspective showing the erected container being closed after it has been filled with its contents;

FIG. 4 is a perspective which shows the closed container being opened; and

FIG. 5 is a perspective which shows the container after it has been opened.

In the drawings, a flat one-piece blank 5, preferably of corrugated paper board, has top, bottom and side portions respectively designated 6, 7, 8 and 9 defined by longitudinal scores 10 and transverse scores 12 which provide fold lines for erecting the box. The body portions 6—9 each have separate end flaps 14 and 15 separated from each other by die cut slots 16. A gluing tab 18 having gluing flaps 19 is integral with the body portion 7.

The side portion 8 has severing means to sever it longitudinally along a tear line 23 including a tear tab 20 which may be conveniently formed by die cutting the material of the portion 8 at a transverse score line 12 and preferably so that it intersects the transverse score line 12. A tear tape 22 is adhesively attached underneath to the material of the side portion 8 so that it extends substantially longitudinally of the side portion 8 from under the tear tab 20 to the opposite transverse score line 12. A second tear tab 24 similar to the tab 20 may be conveniently formed at the opposite end of the side panel 8, preferably intersecting the opposite transverse score line 12, so that the tear line 23 is formed by the tear tape 22 between the tabs 20 and 24.

The end flaps 15 of the side portion 8 have lines of weakness 26 extending substantially from the severing means and along which they are severable under light force when the side portion 8 is severed along the tear line 23.

The other side portion 9 has a longitudinal fold score 28 extending between opposite transverse score lines 12 and its end flaps 15 have lines of weakness 30 extend-

2

ing substantially from the fold score 28 and along which they are severable under light force.

The blank 5 is partially formed by folding it along the longitudinal score lines 10 and then securing the outer longitudinal edges of the body parts 7 and 9 together as by gluing the tab 18 and its end flaps 19 to the side portion 9 and its end flaps 15. This forms a manufacturer's joint so that the blank 5 assumes the condition shown in FIG. 2 in which it may be folded and shipped in flat condition.

When the box is to be filled, it is erected into rectangular condition with the end flaps 14 and 15 of at least one end protruding co-planar with their respective body portions 6—9 and the contents are inserted as by automatic filling machinery in the usual manner through one open end of the erected box. Then the end flaps 15 of the side portions 8 and 9 are turned in at right angles to the body portions 6—9 as seen in FIG. 3 and then the end flaps 14 of the top and bottom portions 6 and 7 are turned over and secured as by gluing to the surfaces of the end flaps 15 on opposite sides of the lines of weakness 26 and 30, so that the closed end of the box assumes the condition seen in FIG. 4. The opposite end of the box is closed in the same manner.

To open the box the tab 20 has been conveniently formed intersecting the transverse score line 12 and it protrudes slightly so that it may be grasped by the thumb and forefinger. Thus it may be torn away from the side portion 8 and toward the opposite end as seen in FIG. 4. Although the tear is made in the material of the body portion 8 so that its edges may be somewhat random and ragged, it is guided and reinforced by the tear tape 22 so that a continuous tear strip is removed from one end of the body portion 8 to the other terminating at the tab 24. Alternatively, the tear may be started by the tear tab 20 and made, say half way along the box, and completed by grasping the other tab 24 and tearing back to complete the removal of a tear strip.

The box may now be opened under light force by severing the end flaps 15 of the side portion 8 along their lines of weakness 26. The end flaps 15 of the other side portion 9 are thereby severed along their lines of weakness 30 and the opening of the box is facilitated by its ability to fold open along the hinge formed by the longitudinal fold score 28 on the opposite side panel 9.

The use of two tabs 20 and 24 serves not only to provide means to start the tear at both ends of the tear line 23 but also by the die cuts by which they are formed to connect the tear line 23 to the lines of weakness 26 so that when the side panel 8 has been severed there remain only the lines of weakness 26 and 30 to be severed under the light pressure necessary to get the box completely open.

It will be observed that the tear tape 22 is applied slightly offset from the lines of weakness 26. This is because the formation of the blanks 5 is a continuous operation in which the tear tape 22 may be continuously laid on to a moving web of the material forming the blanks, after which the blanks are die cut and severed across the outer extremities of the flaps 14 and 15 so that in practice the tear tape extends to the edges of the end flaps 15 of the side portion 8 on which it is laid. The offsetting of the tape 22 is therefore desirable, so that the tape does not cover and interfere with the formation of the lines of weakness 26.

The lines of weakness 26 and 30 are conveniently formed as by partial slitting of the end flaps 15 leaving intermittent bridges of material across them, which may be broken upon severance of the side panel 8 along the tear line 23.

It will be observed that the tear means providing the tear line 23 may be formed on either of the side por-

tions 8 or 9 or on either of the top or bottom portions 6 or 7, and it is also apparent that the provision of the tear means in combination with the associated lines of weakness 26 of the end flaps 15 may be varied without departing from the scope of the invention.

While the container is conveniently formed of corrugated board, which includes a layer of corrugated medium secured to one or more plies of liner board, it is also contemplated that a container of the invention may be made of other material such as a heavy single sheet of paper board.

We claim:

A paper board container having top, bottom and side portions defined by longitudinal and transverse score lines, said portions having separate end flaps, one said portion having severing means to sever it longitudinally including a tear tab formed at a said transverse score line and tear means extending from said tear tab longitudinally substantially to an opposite said transverse score line, the end flaps of said portion having lines of weakness extending substantially from said severing means to the edges of said end flaps, the end flaps of the adjacent portions being secured to said end flaps on opposite sides of said lines of weakness, said end flaps being severable under light force to open said container when said portion is severed, said tear tab intersecting a said transverse score line and a said line of weakness, said severing means being disposed along a side portion and the op-

10
15

posite side portion having a longitudinal fold score extending between transverse score lines and its end flaps having lines of weakness extending substantially from said longitudinal fold score to the edges of said end flaps, the said end flaps of the adjacent portions also being secured to said last mentioned flaps on opposite sides of their said lines of weakness, said end flaps having said lines of weakness being severable under light force to open said container and said longitudinal fold score providing a hinge when said side portion is severed, said tear tab being cut in the material of said portion, a second tear tab cut in the material of said portion and formed at said opposite transverse score line, said tear means including a tear tape attached underneath to the material of said portion and extending from under both said tear tabs to the edges of the end flaps of said portion and said lines of weakness of the end flap of said portion being parallelly offset from said tear tape.
